United States Patent Office

Des. 197,572
Patented Feb. 25, 1964

197,572

CANISTER

Manuel S. Ziskin, Mayfield Heights, Ohio, assignor to Kromex Corporation, Cleveland, Ohio, a corporation of Ohio

Filed Apr. 15, 1963, Ser. No. 74,450

Term of patent 14 years

(Cl. D44—6)

Fig. 1

Fig. 2

FIG. 1 is a top plan view of a canister showing my new design;

FIG. 2 is an elevational view thereof;

FIG. 3 is a bottom plan view thereof, and

FIG. 4 is a cross-sectional view, taken on the line 4—4 of FIG. 1.

I claim:

The ornamental design for a canister, substantially as shown.
